UNITED STATES PATENT OFFICE.

CHARLES E. BANKS AND JOHN W. CHESTNUT, OF NEW CASTLE, PA.

DINNER-PAIL.

SPECIFICATION forming part of Letters Patent No. 284,592, dated September 11, 1883.

Application filed May 16, 1883. (No model.)

To all whom it may concern:

Be it known that we, CHARLES E. BANKS and JOHN W. CHESTNUT, citizens of the United States, residing at New Castle, in the county 5 of Lawrence and State of Pennsylvania, have invented certain new and useful Improvements in Dinner-Pails, of which the following is a specification, reference being had therein to the accompanying drawings, in which—

10 Figure 1 is a perspective of a dinner-pail constructed in accordance with our invention. Fig. 2 is a central vertical section of the same.

Like letters refer to like parts in both figures.

15 A represents the lid or cover, and is secured by a hinge, a , to the body B, which is provided with a bail or handle, B'. At one end of the body apertures b are made, and a larger aperture, b' , having a slide or door, b'' , 20 is provided, for a purpose hereinafter described. Within the pail are two removable compartments, C and D, in each of which the back c and bottom c' are formed of one piece of material, which is bent, as at c'' d' , to form the angle of their jointure one with the other, and in the former compartment the side or walls c^3 other than the back c is or are formed of another single piece of material, and the integral back and bottom piece of 25 each compartment is extended upwardly and bent inwardly to form handles c^4 d^4 , by which each compartment and its contents may be lifted bodily and independently of the other from the pail. The compartment D is provided with a shelf, d^5 , having an upwardly-projecting flange, d^6 , as has also the bottom d' , 30 said shelf being perforated or apertured centrally at d^7 .

E represents a lamp adapted to fit the bottom d' of the compartment D, the burner e being directly below the opening d^7 in the shelf d^5 . The wick-raiser e' is arranged opposite the opening b' , whereby the lamp may be lighted and the wick adjusted through said opening, 40 thus avoiding any necessity of removing the compartment D for such purposes. e^2 is the filling-nozzle of the lamp, and e^3 its handle.

F represents the coffee or other liquid receptacle, and it is formed with a central annular or cone-shaped heat-pipe, f , whereby the 45 heat of the lamp E is utilized in the most com-

pact and advantageous manner. As shown, the pipe f is centrally arranged in and forms a part of the walls of the liquid-receptacle, so that the liquid is contained in an annular reservoir, and is therefore so exposed to the heat as to be quickly warmed to desired temperatures, or, if desired, brought to a boiling-point. f' represents the nozzle of the receptacle, and is provided with a vent, f^2 .

55 In order to provide an escape for the products of combustion and to maintain a current of air for its support in the lamp, an aperture, a' , is formed in the cover at such a point that when closed said aperture registers with the heat-pipe f of the receptacle; and to prevent the escape of either undue heat or smoke into the compartment C a depending pipe, a^2 , is secured to the cover.

60 Any suitable knob or handle may be secured to the cover A to facilitate opening the same, and the heat-pipes f a^2 may be either conical or cylindrical, and the latter may be omitted.

Having described our invention and its operation, what we claim is—

75 1. In a compartment dinner-pail, the compartments having one wall of each extended upwardly and bent to form handles, substantially as specified.

80 2. In a compartment dinner-pail, a compartment provided with a bottom, and a lamp arranged thereon, a shelf centrally apertured, and a liquid-receptacle arranged thereon, substantially as specified.

85 3. In a compartment dinner-pail, the combination of the hinged apertured cover A with the removable compartment D, provided with a liquid-receptacle and a lamp, substantially as specified.

90 4. The combination of the cover A, having the aperture a' , pipe a^2 , the compartment D, having shelf d^5 , apertured at d^7 , the lamp E, liquid-receptacle F, having pipe f , and the body B, having the apertures b b' .

95 In testimony whereof we affix our signatures in presence of two witnesses.

CHARLES E. BANKS.

JOHN W. CHESTNUT.
